UNITED STATES PATENT OFFICE.

ELWOOD GRISSINGER, OF BUFFALO, NEW YORK.

TELEPHONE-RECEIVER.

1,129,087.

Specification of Letters Patent. Patented Feb. 23, 1915.

Application filed November 18, 1911. Serial No. 660,992.

To all whom it may concern:

Be it known that I, ELWOOD GRISSINGER, of Buffalo, in the county of Erie, and in the State of New York, have invented a certain new and useful Improvement in Telephone Receivers, and do hereby declare that the following is a full, clear, and exact description thereof.

My invention relates to an improvement 10 in telephone receivers, in which (a) the vibratory portions of the instruments are so arranged that the forces which are brought to bear upon them are balanced in every direction, and so that as a consequence there 15 is a permanency of adjustment; (b) the natural period of vibration of the moving parts is raised to a pitch beyond the range of vibration of dominant voice sounds, thus eliminating the effects of resonance; (c) damping in the ordinarily accepted form is 20 not employed; (d) the mass of the vibratory portions is reduced as much as possible so that the instruments are sensitive and powerful; and, (e) the reduction of mass of 25 the moving parts, absence of damping, high fundamental frequency and method of supporting armatures upon a sensitive suspension is such that a more nearly perfect transformation of the telephone current waves 30 into sound waves is effected.

The receiver which constitutes an embodiment of my invention is built up of the equivalent of a double watch case receiver, the permanent magnets with their pole 35 pieces being placed back to back. The usual telephone receiver is deficient in power because of the low initial force of attraction between the magnets and the diaphragm. This cannot be increased without increasing 40 the mass of the diaphragm and an increase of diaphragm mass imposes conditions which make for other imperfections in operation. The usual diaphragm of small mass and low capacity for magnetic lines of 45 force, as well as the larger diaphragms of greater mass, give an imperfect transformation from current waves into sound waves, principally because of their resonance factor. Imperfect transformations of complex 50 telephone current waves also result because of the fact that all waves are not transformed with the same relative degree of volume.

Telephone receivers constructed in accordance 55 with the principles herein described

correct for the effects of resonance, transform all waves with the same relative degrees of volume and give greater power.

Instruments which are made in accordance with my invention avoid all of the objections above enumerated. 60

I have shown one embodiment of my invention in the accompanying drawings, in which—

Figure 1 indicates a vertical section of a 65 telephone receiver made in accordance with my invention; Fig. 2 indicates a vertical section of the receiver shown in Fig. 1 but taken on a plane at right angles to the plane upon which the section in Fig. 1 is taken; 70 Fig. 3 is an elevation of the front cover for the receiver casing; Fig. 4 indicates a longitudinal section of the armatures to be used in a slightly modified form of the instrument; Fig. 5 indicates a modification of my 75 invention in which the permanent magnets may be provided with coils to increase their strength; and Fig. 6 indicates a diagrammatic view of a simple form of circuit arrangement in which my receiver may be 80 used.

In the drawings, 1 indicates a receiver casing having a handle 2 attached thereto. The handle 2 is hollow and has an opening 3 at its lower end to receive the end of the telephone cord 4. The rear of the casing 1 is closed by means of a cover 5 which is screw-threaded to the casing, and the front of the casing is covered by means of an ear cap or cover 6, screw-threaded to the casing 1, but 85 having a central opening 7 across which is extended a wire gauze disk 8, maintained in a recess in the face of the cover 6 over the opening 7 by means of a ring 9 fitting in the front of the opening 7. Within the casing 1 90 the operative elements of the receiver are inclosed. The type of receiver shown is constructed by assembling for each of two magnetic units a series of semicircular permanent magnets 10 for each set, to which there are 100 attached soft iron or silicon steel pole pieces 11, which pole pieces carry exciting coils 12. The two units are placed back to back and are clamped tightly together by means of screws 13 (Fig. 2) passing through one of a 105 pair of rings 14 and engaging in threaded apertures in the other ring 14. Each of the rings 14 has at its lower portion a screw 15 which is screw-threaded into the face of the ring 14 and projects beyond the same where 110

it carries a hardened steel grooved roller 16 to support a steel piano wire 17. The ends of the piano wire 17 extend into transverse holes 23 in tapered pins 19, which are supported in similarly shaped openings 18 in the faces of the rings 14. Once that the pins 19 have been adjusted to place the wire 17 under tension, a wedge 20 is inserted between the pins 19 to maintain them in their adjusted positions. After the tapered pins 19 have been adjusted, the wire 17 is put under further tension by means of four adjusting screws 21 which are carried in projections 22 upon the face of the ring 14. The adjustable screws 21 may be constructed in any desired manner so that their inner ends bear against the wire 17. The casing 1 is provided with apertures 21^a to render the adjustable screws 21 accessible without removing the casing.

An armature support 23 extends from the front to the rear of the receiver casing 1 between the two pairs of poles 11, said armature support having screw-threaded thereto a pair of armatures 24, the faces of which extend over the ends of the pole pieces 12. A pair of lock nuts 25 are screwed upon the armature support 23 to maintain the armatures 24 in their adjusted position. It is intended that the lock nuts 25 shall also support upon their outer faces the wire 17. Beyond the wire 17 the rod 23 carries at the rear of the casing another lock nut 26, and at the front of the casing 35 an armature type of diaphragm 27, that is to say, a diaphragm having a free edge, which occupies a position immediately behind the opening 7 in the ear cap 6.

The windings 12 of the receiver coils are 40 preferably connected each pair in series and the two pairs together in multiple relation through two pairs of terminals 28 and 29, which are made a part of an insulating block 30, which block is attached by 45 screws 31 to the casing 1. The receiver cord 4 passing through the hollow handle 2 is attached to the terminals 29 which are in electrical contact with the terminals 28. The hollow handle 2 is attached to the block 50 by being threaded thereon.

Instead of using the armature diaphragm 27, I may make use of the ordinary type of vibratory diaphragm, as shown in Fig. 4. In this figure 32 indicates the ordinary type 55 of vibratory diaphragm which is attached to the end of the rod 23 by means of a pair of nuts 33 located on opposite sides of the diaphragm 32. The diaphragm 32 is maintained in position at its periphery by being 60 clamped between the casing 1 and the ear cap 6 or in any other suitable manner.

As shown in Fig. 5, I may equip the permanent magnets 10 with special exciting coils 34 to increase their strength, which 65 coils derive their energy from the same

current which passes through the transmitter. The coils 34 are preferably wound upon copper bobbins 35 to act as a sheath so that telephone currents passing through the coils do not, in any case, affect the magnetic field or the receiver. In this construction it is preferable that the coils 34 and 12 shall be electrically connected in series multiple relation. 70

In Fig. 6 I have shown a simple form of 75 circuit arrangement in which my transmitter may be used. In this figure Tr. indicates the transmitter, b indicates the battery of the local transmitter circuit L, p, p indicate the primaries of the induction coil 80 located in said circuit, s indicates the secondary of said induction coil which is located in the main circuit m, said circuit also including the receiver R, and a bell B¹ bridges across the main line m. 85

The operation of the receiver is as follows: There are two magnetic fields created by the permanent magnet 10 and these fields exert an initial attraction upon the armatures 24 which are closely adjacent to the 90 faces of the pole pieces 11. The action of the two magnetic fields upon the armatures is such as to be opposite and equal, thereby equalizing the initial pull. The connections of the receiver coils, however, to the telephone circuit are such that, if the electrical waves traversing the one set of coils 12 tend to attract the armature more strongly toward their respective pole pieces, the same 95 electrical waves passing through the opposite exciting coils 12 tend to lessen the degree of attraction between their pole pieces and armature. The result is a displacement of the armatures bodily in one direction. In this manner a vibration of the armatures and the wire suspension is set up by the telephone current waves and this vibration is manifest in a movement of the armature diaphragm 27. In the case where the diaphragm 32 of the ordinary type is 100 used, the vibrations are communicated to it instead of to the armature diaphragm 27. The supporting of the vibratory portion of the instrument upon the wire suspension as shown, and the extreme tension of the latter 105 as produced by the winding pins and the lateral deflecting members 21, prevents resonance of the apparatus and provides a more nearly perfect transformation of the current variations into mechanical vibrations of the armature. 110

While I have described my invention above in detail, I wish it to be understood that many changes may be made therein without departing from the spirit of the apparatus. 115

I claim:

1. A telephone receiver comprising a vibratory element, a movable armature attached thereto, a magnet for moving the 120

130

armature, and means for balancing the armature by means of oppositely acting forces, comprising wire supports placed under tension by bowing.

2. Apparatus of the kind described comprising an electro-magnet, an armature therefor and a suspension for such armature comprising a wire, means for imparting high initial tension thereto, bearings for said wire intermediate of the said tension means, and a connection between the central portion of the wire and the said armature.

3. Apparatus of the kind described comprising an electro-magnet subject to variation by electrical voice current, an armature therefor, a wire connected to the armature, means for holding the wire in a state of high initial tension and means acting transversely to the wire for deflecting the same out of a straight line and in a direction that is transverse to the direction of vibratory movement of the armature.

4. Apparatus of the kind described comprising an electro-magnet subject to variation by electrical voice current, an armature therefor, two adjacent wires stretched under high initial tension across the line of movement of the armature and secured thereto, and means acting transversely to such line for deflecting the said wires in their common

plane and adapted to increase the fundamental frequency thereof.

5. The combination of an electro-magnet subject to variation by electrical voice current, an armature therefor, and means for imposing a high natural frequency upon the said armature comprising a wire connected thereto, means for holding the same under high initial tension, and means intermediate such holding means, adapted for adjustment to deflect said wire from a straight line and transversely to the direction of vibration of the armature.

6. The combination of an electro-magnet, an armature therefor and means for imposing a high fundamental frequency upon said armature and the parts vibrating therewith comprising two adjacent and substantially parallel wires, means for holding the same under a high tension, and thrust screws acting on said wires to deflect them in their common plane, thereby shortening the effective length of said wires and increasing the frequency thereof.

In testimony that I claim the foregoing I have hereunto set my hand.

ELWOOD GRISSINGER.
